UNITED STATES PATENT OFFICE.

FREDERICK JOHN TURNER BELL, OF BURY, AND HARDY CECIL BELL, OF PADIHAM, ENGLAND, ASSIGNEES TO TWIN BOBBIN SEWING MACHINE COMPANY LIMITED, OF BURY, ENGLAND, A LIMITED LIABILITY COMPANY.

SEWING-MACHINE.

1,185,364.

Specification of Letters Patent.

Patented May 30, 1916.

Application filed October 6, 1911. Serial No. 653,140.

To all whom it may concern:

Be it known that we, FREDERICK JOHN TURNER BELL, a resident of Bury, in the county of Lancaster, England, and HARDY CECIL BELL, a resident of Padiham, in the county of Lancaster, England, both subjects of the King of Great Britain and Ireland, have invented new and useful Improvements in Sewing-Machines, of which the following is a specification.

This invention relates to sewing machines of that type in which the rotary reel casing or loop divider or equivalent is driven by or from pins rotating around an axis which is not quite in prolongation of the axis of the reel casing or the like but is slightly inclined therefrom. The pins alternately engage with and disengage from holes formed in the reel casing to drive it around while at the same time permitting the passage around the casing of the needle thread loop. One form of such driving apparatus and reel casing is described in the specification to British Letters Patent No. 5247 of 1909. In that specification two driving pins are described. Other numbers of driving pins alternately engaging with and disengaging from an equivalent casing are, however, known.

According to this present invention three driving pins are engaged to rotate a reel casing, the three driving pins being so arranged and disposed relatively to the casing that there is never more than one of them out of engagement with the casing at any one time, to permit the passage of the needle thread loop while at times all three are in engagement. Also, and with the reel casing indicated and herein described and illustrated, the pin which engages with the reel casing immediately behind the rear edge of the notch or gap in which the needle thread loop is formed, does so immediately after the loop of needle thread which has been engaged by the hook has passed inward along the face of the rear edge of the notch or gap to the inside of the circular path described by such pin. The hole for engagement with a pin which is next behind the rear edge of the notch or gap is preferably as near to such rear edge as it can be formed.

A guard plate or guard plates consisting

of a stationary member or of stationary members bridging completely over the gap in the race into which the needle descends and as described in our British Letters Patent No. 3455 of 1910 may be used between the rotary reel casing and the disengaged driving pin so as to prevent the needle thread loop ballooning and becoming entangled by this pin. The disengaged pin passes closely directly over the outer side of such a guard plate.

In order to insure that the needle thread loop shall as soon as possible be carried to the bottom of the notch or gap in the reel casing, to enable the disengaged driving pin to be again engaged with its casing as soon as possible, to give the minimum amount of thread to be taken up by the take up motion, and to insure that a regular and equal amount of thread will always be formed into a loop at each stitch, we place what we will term a "spreader" in the path of the needle thread loop, the point of which "spreader" will enter the loop immediately the loop has been engaged by the hook on the reel casing. The spreader is stationary and has an edge or inclined surface which will, acting in co-operation with the rear edge of the gap in the divider, direct the needle thread down to the bottom of the gap in the casing as the latter rotates. When the loop is engaged by the spreader the rear edge of the gap in the casing crosses the line of the guiding edge of the spreader at such an angle that as the rotation of the casing continues the point of intersection moves toward the bottom of the gap in the casing and the needle thread which is jointly engaged by the spreader and the rear edge of the gap in the casing moves with such point of intersection.

The rotary reel casing we prefer to employ is of the construction shown in the drawings and referred to herein, and it is preferably provided with a reel carrier of the construction described and illustrated.

Figure 1 illustrates in end elevation the reel casing, the three pin driving device therefor, and the spreader. Fig. 2 is an edge view of the same devices. Figs. 3, 4, and 5 illustrate the spreader and the co-operating part of the reel casing in different positions. Fig. 6 is a vertical longitudinal

section of the reel carrier which it is preferred to employ. Fig. 7 is a view of such reel carrier taken from below.

5 A is the rotary reel casing consisting of two conical parts or shells *a* and *b*, one, *b*, being flatter than the other, jointed together at their bases and rotating in the race B.

10 C is a single deep notch or gap formed in the casing and D is a hook formed in the periphery of the casing at the rear face of such gap to engage with the needle thread loop. These are all known.

15 The shell *b* is provided with three driving holes in which engage the three pins E, E¹, E² carried by arms of equal length equally disposed around a driving shaft S. The driving shaft has its axis so obliquely disposed to the axis of the reel casing and the 20 pins are of such length that two of the pins are always engaged with their holes in the casing and that there is never more than one pin out of engagement with its driving hole in the reel casing at any one time. At other 25 times all three pins are in engagement with their driving holes in the reel casing at one and the same time.

With the pins in the position shown in Fig. 2 of the drawings the pin occupying 30 the lowest position is in deepest engagement with the casing. The other two pins being at the same vertical height are both engaged with their driving holes but not deeply. As rotation of the casing takes place in the 35 direction of the arrow, Fig. 1, the pin of these latter two which is ascending comes more and more out of engagement with its driving hole until it is free therefrom when it arrives at about the position indicated at 40 E² in Fig. 1. There is now a slight gap between the end of such pin and the reel casing and the needle thread loop which is now being taken up by the hook D of the casing can pass along the rear face of the 45 notch or gap C in the casing between the end of the disengaged pin and the reel casing. By the time this pin, while descending, again comes to about the vertical height in which it is represented in Fig. 2, the needle 50 thread loop has passed it and the pin is again in engagement with its reel casing. Each pin in turn engages with and disengages from the casing in the same manner. The manner in which the needle thread loop 55 passes between a disengaged pin and the reel casing when being taken up by the reel casing or being delivered therefrom is well known.

Fixed closely adjacent to the rotary casing and so that its upper point is in the path of the needle thread loop carried around by the hook of the rotary casing is the fixed spreader. This spreader is a smooth metallic and thin plate G so fixed relatively 60 to the rotary casing A and the hole through

which the needle thread passes through the machine bed plate H, as to engage with the needle thread loop by entering it and to remain engaged or entered in such loop until the loop has been pushed down by the 70 spreader to about the bottom or inner part of the gap in the rotary casing.

In Fig. 1 the hook D of the rotary casing is shown as just engaging with the loop of the needle thread X. In Fig. 3 the rotary casing is shown as having moved slightly 75 onward and shows the point of the spreader as just about entering the loop of needle thread which is being carried around by the rotary casing. In Fig. 4 the rotary casing is shown as having progressed farther in its rotation. The point of the spreader G is still entered into or contained within the needle thread loop. That part of the needle thread which passes from the hole in the bed plate to and through the gap or notch on that side of the rotary casing on which the spreader is placed, thus passes over the outer face or part of the outer face of the spreader G and to do this crosses over the 80 front or leading edge of the spreader. This leading edge of the spreader is so shaped and so coöperates with the rear edge of the gap or notch C that as the thread loop is carried around by such rear edge of the 85 gap the leading edge of the spreader which is crossed by the needle thread loop pushes such loop down the rear edge of the gap until it has reached the innermost portion of that edge. This position has been reached 90 when the rotary reel casing is in the position of Fig. 5, and the thread may now have been pushed to a position in which it has passed off the spreader, or if the upper part of the spreader is still in the loop the continued rotation of the rotary casing from the position shown in Fig. 5 will move the loop bodily away from the spreader and draw it off it.

Although a spreader is shown on one side 100 only of the casing a second and similar spreader may be used on the other side of the casing similarly coöperating with the rear edge of the gap.

Figs. 6 and 7 represent an improved form 115 of reel carrier for use in the reel casing. This reel carrier is provided with a plate R at its lowest part and opposite to the delivery eye J of the underthread, which lower plate acts as a counterweight to insure the 120 reel carrier remaining in its proper position when employed with a rotary casing rotating around an approximately horizontal axis even when the carrier is not engaged by its gate or retaining device, and also 125 serves as part of the threading device for the underthread. This plate extends about parallel with the spindle on which the reel is placed. It has a slit extending from one edge through which the reel thread is drawn 130

without threading. From the inner end of this slit the thread passes along the outside of the plate under a tension spring K. The thread then passes up along the outer 5 face of the reel carrier in a slight groove formed along the projection L with which an ordinary hinged gate engages and passes up to the delivery eye or like part J. The passage to this delivery eye is in a groove 10 formed in the metal, in which groove the thread is easily laid, and the groove takes a helical twist or turn on its way to the delivery point or eye.

M is a small tube fixed to the carrier and 15 adapted to fit upon the spindle or pin F in the rotary reel casing.

N is a second tube mounted so as to rotate upon the first tube M and provided externally with spring bows O by means of 20 which a reel P placed over them is snugly and securely held. A smooth and concentric rotation of the reel upon its spindle carrier is thus insured.

We claim:—

25 1. In a sewing machine driving device of the type wherein a rotary shuttle is driven by driving pins engaging holes in the shuttle, the combination of a horizontal driving shaft, three driving arms fixed to 20 such shaft and at right angles to the plane of the longitudinal axis of said shaft, a pin at the end of each of said arms, and a shuttle with holes formed therein in which said pins engage, the shuttle being placed at

such an angle that two at least of the pins 35 are always in driving engagement in their holes in the shuttle and sometimes three, while allowing free passage for the needle thread loop around the shuttle, thus insuring smooth working at high speeds without 40 shock or jar, a notch in the shuttle forming a hook for the needle thread loop, and an engaging device for the loop formed with an edge oblique to the loop taking hook and so formed and arranged that every loop 45 taken is immediately and positively pushed to the bottom of the notch to insure that the loop shall in every case reach the bottom of the notch as soon as taken, and that every loop shall have the same quantity of thread, 50 substantially as described.

2. In combination with a rotary shuttle for a sewing machine, a reel carrier having a counterweight plate to prevent rotation of said reel carrier, a slot in the counterweight plate through which the thread passes and a thread tensioning spring secured to the counterweight plate itself, substantially as and for the purpose set forth.

55 In witness whereof we have hereunto set 60 our hands in the presence of two subscribing witnesses.
